UNITED STATES PATENT OFFICE.

OTTO A. WALSTAD, OF MINNEAPOLIS, MINNESOTA.

DETACHABLE WINDOW.

Application filed February 11, 1924. Serial No. 692,063.

To all whom it may concern:

Be it known that I, Otto A. WALSTAD, a citizen of the United States, resident of Minneapolis, county of Hennepin, and State of Minnesota, have invented certain new and useful Improvements in Detachable Windows, of which the following is a specification.

The object of my invention is to provide a window in the construction and use of which sash pockets and window weights are entirely eliminated, thereby permitting the insertion of a window into a smaller space and allowing windows to be arranged nearer together than where the usual sash weight pockets are necessary.

A further object is to provide a window having sash which can be easily and quickly detached from the frame and reversed if desired for cleaning or other purposes.

A further object is to provide a window mounted in such a way in the sash that wind and dust can not work into the room around the window and the use of the ordinary weather strip is rendered unnecessary.

A further object is to provide a window in which one or both sash may be made removable and either sash, when so constructed, can be adjusted at any point in its frame and held in such adjustment without the use of weights or spring catches.

Other objects of the invention will appear from the following detailed description.

The invention consists generally in various constructions and combinations, all as hereinafter described and particularly pointed out in the claims.

In the accompanying drawings forming part of this specification,

Figure 1 is a front elevation of a window embodying my invention,

Figure 2 is a vertical sectional view of the same;

Figure 3 is a sectional view on the line 3-3 of Figure 1;

Figure 4 is a sectional view on the line 4-4 of Figure 1;

Figure 5 is a sectional view on the line 5-5 of Figure 1;

Figure 6 is a vertical sectional view of a window, showing both the upper and lower sash adjustably and removably mounted within the frame.

In the drawing, 2 represents the head rail of the window frame, 3 the side rails or stiles and 4 the bottom rail, all of any ordinary or preferred construction, preferably wood.

The upper and lower sash comprise side rails 5 and end rails 6 composed preferably of metal, having mitered corners securing the abutting ends of the rails together, said rails being substantially S-shaped in cross section, forming longitudinal recesses 7 and 8 with flanges 9 and 9a forming the outer walls of these recesses in substantially parallel relation, see Figure 3.

Blocks 10 of suitable material, preferably wood, are fitted into the recess 7 and have rabbets 11 in their outer edges wherein the light of glass 12 is seated, the rabbet being of sufficient depth so that the outer surface of the glass is flush substantially with the surface of the block.

The blocks are seated against the middle portion of the rails, joining the inner and outer flanges, as shown in Figure 4, and the blocks are of substantial width, so that they extend approximately to the rear wall of the recess and effectually close the joint around the glass to the entrance of air or moisture.

Spring plates 13, preferably of metal, are interposed between the face of the glass and the flanges 9, as shown in Figure 4, one longitudinal edge of the plate resting on the block 10 and the other corresponding edge being seated on the surface of the glass, holding it snugly on its seat with a yielding pressure.

The side rails 3 of the window frame are provided preferably with metallic face plates 15 which extend from the lower rail 4 to the upper rail 2. Spring guide plates 16 are mounted upon the face plates 15 and secured to the side rails 3 by suitable means such as nails 17, as shown in Figure 3, the spring guide plate normally bearing at one side upon the face plates 15 but capable of being separated therefrom.

These guide plates extend from the ends of the window frame side rails on both sides to points near the middle portion thereof, as indicated in Figure 1, and the inner ends 18 of these plates are preferably turned outwardly, as indicated to form guides for the flanges 9a of the window sash, see Figure 3, where the flange 9a is shown inserted between the face plate 15 and the guide plate 16 and held by frictional engagement with said plates in

any position in the opening or closing of the sash. The side and end rails of the sash are made in substantially the same manner, S-shaped in cross section, the only difference being that the side rails are longer than those at the top and bottom. This construction permits convenient assembling, any two rails serving for the side rails of the sash and the top and bottom rails may be easily 10 picked and fitted in place without any adjustment or locking for specially made parts.

Both sides of the window at the top and bottom are equipped with these guide plates 16, with a gap between the adjacent ends 15 near the middle of the window, as shown plainly in Figure 1, so that the upper end of the lower sash, when it is in its closed position, will be out of engagement with the upper guides and if it is desired to remove 20 the sash, it is only necessary to raise the lower sash until its lower portion is out of engagement with the lower guide plates 16, then pull its lower portion slightly outward, as shown in Figure 2, and lower it 25 outside of the lower guide plates 16 until it is released from the upper guide plates. The sash may then be removed from the window. The same operation applies to the upper sash, only the movement will be 30 reversed.

For the purpose of holding the guide strips or plates with a yielding pressure against the sash, I prefer to provide the side rails of the frame with clamping strips 35 or bars 19 having inwardly turned portions 20 adapted to bear on the guide plates 16 for holding them with an increasing or decreasing pressure, as preferred, against the flanges 9^a so that sufficient friction will be 40 produced for holding the sash vertically in any adjusted position, (Fig. 3). The pressure of these clamping bars on the guide plates may be increased or decreased by suitable means, such as screws 21, which pass 45 through the bars into the side rails of the frame. Tightening these screws will increase the pressure of the guide plates on the sash and loosening the screws will relieve such pressure. Evidently, as indicated 50 in Figure 5, with the flange 9^a sliding under the guide plates, there will be no possibility of air or dust entering the house around the rails of the sash, a dust and air tight joint being formed at this point. At the 55 same time, whenever desired, the sash can be easily and quickly detached from the guides as above described. The guides may be made of any suitable material, but preferably of a light, thin gauge of metal 60 which will yield and adapt itself to the positions of the sash and at the same time will hug the flanges thereof and hold the sash in any position in which it may be adjusted.

65 In Figures 1 and 2, there is shown a win-

dow frame having only the lower sash 70 adjustably and removably mounted therein, while the upper sash is fixedly mounted, the light of glass 22 being seated in the center rail 23, the side rails 3 and the top rail 2 of the window frame. To prevent air, dust, and water from entering the room between the bottom of the sash and the bottom rail, the bottom rail 4 of the frame has a plate 24 secured thereto; this plate having a looped or folded longitudinal edge 25 that 75 is adapted to enter the recess 8 in the bottom rails when the lower sash is closed as indicated in Figure 5, thus forming air and dust-tight joints at this point.

Means are also provided for the purpose of providing an air and dust-tight joint 80 between the upper portion of the sash and the center rail 23 of the window frame, when the sash is in its down or closed position. A recess 26 is preferably provided in the lower portion of the center rail 23 adjacent the sash, adapted to receive therein a flexible weather stripping 85 consisting of a strip 27 of suitable fabric, which is secured to the center rail by suitable means such as a bar 28. Against this flexible weather stripping the flange 9^a 90 is seated when the sash is in its closed position, as indicated in Figure 4.

In Figure 6, I have shown a modified construction in which both the upper and lower sash of the window are adjustably and removably mounted in the frame. In this figure it will be noted that the details 100 of construction of each sash and also the supporting means therefor, are substantially identical to the details of construction of the removable sash and supporting means, shown in Figure 2, and it is therefore unnecessary to describe same in detail, like parts being represented by like reference numerals. The lower sash in Figure 6 is shown in its down or closed position, its operation, however, being similar to that 105 of the lower sash, shown in Figure 2. The upper sash in Figure 6 is also shown in closed position, the recess 8 in the upper rail 6 of the sash being in engagement with the depending looped portion of the plate 24, secured to the upper rail 2 of the window frame, and also the inner rounded surface 110 of the flange 9^a of the lower rail 6 of the sash is bearing against the flexible weather strip 27, secured to the upper portion of the center rail 23 of the frame. To remove the upper sash from the frame it is only necessary to give it a slight pull outwardly sufficient to allow the flange 9^a to clear the 115 outwardly turned ends 18 of the lower guide plates 16, then pull it downwardly until the flange 9^a disengages the guide plates 16 and face plates 15. The sash may then be removed from the frame for washing or for 120 any other purpose, as desired. To replace 125

the sash in the frame the upper edge of the flange 9^a of the upper portion of the sash is placed against the face plates 15 between the outwardly turned ends 18 of the guide plates 16. It is then moved upwardly and as the flange 9^a engages the ends 18 of the upper guide plates 16 it will force the plates 16 outwardly and pass upwardly between them and the face plates 15, as clearly shown in Figure 3, until it reaches the position shown in Figure 6. It may then be released, the spring guide plates 16 effectually holding the sash in place while at the same time allowing it to be moved vertically in its guides the tension of the plates 16 against the flange 9^a being sufficient to hold the sash in its adjusted positions.

I claim as my invention:

1. The combination, with a window frame and a sash mounted to move vertically therein, of guides arranged to bear on said sash with a yielding pressure, said guides having gaps therein near the middle portion of the window frame and permitting the sash to be disengaged at one end from said guides and removed from said frame during the vertical movement of said sash.

2. The combination, with a window frame and a sash therefor, of guides mounted in said frame and extending from the upper and lower ends thereof to a point near the middle of the frame, there being a gap between the adjacent guides at their inner ends, said guides being mounted to engage said sash successively upon its vertical movement, or said sash may be disengaged from one set of guides during such movement to permit the removal of the sash from the window.

3. The combination, with a window frame and a sash vertically movable therein, of spring metal guides mounted in said frame to engage said sash, said guides being arranged in pairs at the upper and lower ends of the window frame, and having gaps between the guides on the same side of the frame near the middle thereof, the spring of said guides allowing them to be pressed out of the path of said sash to allow either end thereof to clear the guides and be disengaged from the window.

4. The combination, with a window frame and a sash therein having side rails provided with vertical flanges thereon, guides mounted on the side rails of said frame and extending from end to end of said frame and bearing on said flanges for holding said sash at any point in its vertical movement, said guides being mounted to allow said sash to be disengaged therefrom by vertical movement of said sash in said window frame.

5. The combination, with a window frame and a sash movable therein, of guides mounted to bear on said sash and hold it

in its adjusted positions and permit separation of the sash from the window by vertical movement of said sash, and means for increasing or decreasing the pressure of said guides on said sash.

6. The combination, with a window frame and a sash movable therein having flanges on its side rails, of spring metal guides mounted to bear on said flanges and hold said sash in its adjusted positions, and bars mounted to bear on said guides for increasing and decreasing the pressure thereof on said sash.

7. The combination, with a window frame and a sash mounted therein having an end rail provided with a recess therein and guides for the side rails of said sash, a plate mounted on the end rails of said frame and having a flexible loop formed therein to bear on the sash and enter the recess in the end rail of said sash.

8. The combination, with a window frame and upper and lower sash therefor, of guides mounted in the side rails of said frame to engage the rails of said sash, a gap being formed between the upper and lower sash when in their closed position, and a center rail for said frame arranged to close said gap and having recesses therein and weather strips mounted in said recesses for contact with said sash.

9. The combination with a window frame, and a sash vertically movable therein, and comprising side rails substantially S-shaped in cross section, and provided with inner and outer flanges and an intermediate connecting wall between them, said inner flanges being seated upon said window frame, a glass plate supported between said outer flanges and said intermediate wall, and spring guides mounted on said frame and bearing on said inner flanges and holding them against said frame with a yielding pressure.

10. The combination with a window frame, and a sash vertically movable therein, and comprising side rails substantially S-shaped in cross section, forming inner and outer flanges and an intermediate connecting wall between them; said inner flanges being seated upon said window frame, a glass plate supported between said outer flanges and said intermediate wall and spring guides mounted on said frame and bearing on said inner flanges and holding them against said frame with a yielding pressure, said guides having gaps near their middle portions through which said sash may be moved to mount it in said frame or separate it therefrom.

11. The combination with a window frame, and a sash vertically movable therein, and comprising side rails substantially S-shaped in cross section, forming inner and outer flanges and an intermediate connecting wall

between them, said inner flanges being seated upon said window frame, a glass plate supported between said outer flanges and said intermediate wall, spring guides mounted on 5 said frame and bearing on said inner flanges and holding them against said frame with a yielding pressure, and bars mounted on said window frame and bearing on said guides for increasing or decreasing the pressure 10 thereof on said sash flanges.

12. The combination with a window frame, of a sash comprising side rails having inner flanges adapted to slide on the window frame, spring guides secured to the window frame 15 and lapping the edges of said flanges and bearing thereon with a yielding pressure, said guides being arranged in pairs in the upper and lower portions of the window, and having gaps between the opposite guides 20 on the same side of the window, the sash adapted to pass vertically from one guide to the other, and outward pull on the sash allowing it to clear one pair of guides and upon continued movement pass out of engagement with the other pair.

13. The combination with a window frame, of a sash comprising side rails having inner flanges adapted to slide on the window frame, spring guides secured to the window frame 30 and lapping the edges of said flanges and bearing thereon with a yielding pressure, said guides being arranged in pairs in the upper and lower portions of the window, and having gaps between the opposite guides on 35 the same side of the window, the sash adapted to pass vertically from one guide to the other, and outward pull on the sash allowing it to clear one pair of guides and upon continued movement pass out of engagement 40 with the other pair, and means mounted on the window frame for concealing the outer portion of said guides and regulating the pressure thereof on said sash flanges.

14. In a window, a frame, resilient guides 45 whereon said frame is adapted to slide from end to end of the window, the engagement of said guides with said frame holding it in its adjusted positions without the use of weights and said frame being adapted to pass out of 50 or into engagement with said guides during its vertical movement thereon.

15. In a window, a sash, resilient guides whereon said sash is adapted to slide and is frictionally held in its adjusted positions 55 without the use of weights, said guides being adapted for the separation of said sash

therefrom or its engagement therewith during its movement thereon.

16. In a window, an upper and lower sash, guides whereon said sash are slidable to an 60 open or closed position, said sash being held in said guides without the use of weights, and said guides being adapted for the respective engagement of said sash therewith or their disengagement therefrom at a predetermined point in their movement thereon.

17. In a window, a frame, guides comprising upper and lower portions wherein said frame is supported, said guides being adapted to direct said frame from one portion to 70 the other or allow said frame to be separated from either portion.

18. In a window, guides for the upper and lower sash, said guides being adapted to hold the sash in their adjusted positions without the use of weights and allow either sash to be disengaged from its guides or engaged 75 therewith during its movement thereon.

19. In a window, a sash, guides therefor comprising fixed and resilient members between which the sash is slidably held in its 80 adjusted positions.

20. In a window, a sash, guides therefor comprising fixed and resilient members between which the sash is slidably held in its 85 adjusted positions, said guides being adapted for guiding the sash throughout the height of the window and for allowing its separation from the guides at a predetermined point thereon.

21. In a window, a frame, guides wherein said frame is held and supported in its adjusted positions, said guides having gaps therein to adapt them for the separation of 90 said frame therefrom during such movement.

22. The combination with a window frame and upper and lower sash therefor, of guides for the rails of said sash, a gap being formed between the upper and lower sash when in 100 their closed position, and means for closing said gap and having weather strips for contact with said sash.

23. In a window, a sash comprising rails and a glass plate seated thereon, flanges for said rails and guides therefor on the window frame and spring plates interposed between said flanges and said rails and glass plate and bearing thereon.

In witness whereof, I have hereunto set my hand this 8th day of February 1924.

OTTO A. WALSTAD.
